UNITED STATES PATENT OFFICE

SWITS CONDÉ, OF OSWEGO, NEW YORK.

DESIGN FOR A KNIT FABRIC.

SPECIFICATION forming part of Design No. 14,003, dated June 26, 1883.

Application filed April 25, 1883. Term of patent 7 years.

To all whom it may concern:

Be it known that I, SWITS CONDÉ, of Oswego, in the county of Oswego, in the State of New York, have invented new and useful Improvements in Design for a Knit Fabric, of which the following, taken in connection with the accompanying drawing, is a full, clear, and exact description.

This design consists in a novel arrangement of parallel rows of dots and alternate wide and narrow continuous stripes between said rows, as hereinafter more fully explained.

The accompanying drawing illustrates a piece of knit fabric embodying my design.

A A represent the parallel rows of dots, between which run alternately wide and narrow continuous stripes, as shown.

What I claim is—

The design for knit fabric, consisting of parallel rows of dots and intervening alternate wide and narrow continuous stripes, substantially as described and shown.

In testimony whereof I have hereunto signed my name and affixed my seal, in the presence of two attesting witnesses, at Oswego, in the county of Oswego, in the State of New York, this 3d day of April, 1883.

SWITS CONDÉ. [L. S.]
